WARP-DRAWING MACHINE AND MECHANISM FOR MANIPULATING DETACHED HEDDLES THEREIN.

1,215,789.

Specification of Letters Patent. Patented Feb. 13, 1917.

Application filed February 10, 1904. Serial No. 192,921.

To all whom it may concern:

Be it known that we, MILLARD F. FIELD, of Winthrop, and EDGAR F. HATHAWAY and CHARLES D. LANNING, both of Boston, all 5 in the county of Suffolk and Commonwealth of Massachusetts, have invented certain Improvements in Warp-Drawing Machines and in Mechanism for Manipulating Detached Heddles Therein, of which the following is a specification.

The invention relates to warp-drawing machines, more particularly for drawing warp-threads into or through the eyes or openings of thread receiving loom elements 15 such as heddles separate from one another and detached from their usual harness supports, or of devices such as metallic drop-bars, sometimes called drop-heddles, for stop-motion, which are employed in connection with the warps in a loom, and to 20 mechanism for controlling and manipulating such detached heddles; and this latter mechanism consists in a reservoir or holder for such detached heddles or devices, in 25 which they are arranged preferably in a compact series; means by which this series of devices are pressed toward one side of the holder where an outlet is provided to permit a single heddle at a time to be withdrawn 30 from the series; mechanism to separate a single heddle or other device from the compact series and place it with its eye in proper position for the drawing-in operation; means to deposit the said heddles or 35 other devices in regular sequence in one or more separate series, and in the combination of the above mentioned mechanism with the mechanism usually embodied in warp-drawing machines.

40 In the drawings forming a part of this specification—

Figure 1 is an end elevation of a warp-drawing machine with all the parts assembled, including the present improvements;

45 Fig. 2 is a plan view with portions of the upper parts of the machine removed;

Fig. 3 is an end elevation of the mechanism by which the heddles or other devices are held and transferred from one position to another for the drawing-in opera-

tion, and deposited in regular compact sequence after the warps are drawn-in;

Fig. 4 is a front elevation of the same mechanism;

Fig. 5 is an edge view of one form of 55 device for engaging the heddles and transferring them to the position for drawing warps into their eyes;

Fig. 6 is a front view of the same device;

Figs. 7 and 8 are respectively edge and 60 front views of one side of the guide-ways for the transferring device with means at the lower end for releasing the heddle from the transferring device;

Fig. 9 is a cross-section on line 9—9, Fig. 65 4, of the guide-way for the heddles and transferring device, and the means by which the heddles are turned at a right angle when removed from the guide-way;

Fig. 10 is a detail showing an oscillating 70 receptacle provided with two chambers for receiving the heddles and holding them in two compact series after the warps have been drawn-in.

The warp-drawing machine illustrated in 75 the drawings is similar to that described and shown in application No. 142,251, filed February 12, 1903, with the addition of a reservoir or magazine for heddles which may also be employed as stop-motion drop-bars and the mechanism for controlling and 80 manipulating these heddles.

Referring to the drawings, A is the traversing carriage which supports the drawing-in device a', and its driving mechanism; B 85 is one of the main standards of the machine, and B' a standard which supports the reservoir for the detached heddles and the transferring mechanism and is supported on the carriage A. (See Fig. 2). E is the reed, and e' a spiral reel opener which by its 90 operation also adjusts the reed differentially and independently upon its bearings in a direction parallel with the traverse of the carriage A, whereby the successive reed-dents are placed accurately in the path of the drawing-in device a' substantially as set forth in said application No. 142,251. H, 95 are loom harnesses; are worms which feed the attached heddles of the loom-harnesses 100

and locate the eyes thereof in position for the drawing-in device; s^2 is the screw which separates and feeds the warp-threads into proper position to be caught by the drawing-in device a' . The reed opener e' , the worms i' and warp-thread separating screw s^2 , are all supported upon extensions of or brackets upon the traversing carriage A, and normally move with it. W, the frame which 5 supports the warp-clamps w^3 , w^4 and this warp-frame W is fed or adjusted independently of and differentially to the movement of the carriage A, by means of a worm-wheel f^2 which engages a rack on a bar F attached 10 to the frame W. The worm f^2 is turned by an engaging pawl f^5 which is connected with a rod f^6 , which latter is caused to reciprocate by means of a cam on the feed screw-shaft of the carriage A. In this machine 15 the end of the shaft of the feed-screw s^2 , opposite to the driving mechanism, is supported in a hinged bracket B^2 , which may be swung upward upon its pivot b^3 to afford ample space for inserting and removing the 20 harnesses and their feed-worms i' . This bracket B^2 is attached to the standard B' . The detached heddles d , shown, are intended to be hung upon the warps when in proper 25 position in the loom, and to serve as drop-bars to operate a stop-motion whenever a warp-thread breaks. In the inclined reservoir R the drop-heddles d are placed in a compact mass where they are supported by external contact or engagement only, with a 30 weight r' back of them to serve as a follower to press the series of heddles forward against the front end of the reservoir. In the bottom of the reservoir in line with the inner surface of its front wall is a narrow slot, 35 just large enough to permit a single perforated heddle to pass through, and this front wall of the reservoir is provided with a slot of a width about equal to the cross-sectional diameter of the eye or perforation in the 40 heddle d . In front of the forward end of the reservoir and extending vertically from the top thereof downward to a point a little below the plane in which the drawing-in device reciprocates, is a guide-way formed 45 back of the two plates g , g' , for a sliding piece t , which may be called a heddle transferring device. This transferring device is 50 made up of two parts, one part provided with tongues t' along each edge, which are engaged by and slide in grooves g^8 back of the guide plates g , g' (see Fig. 9), and another part t^2 , of a width less than the slot between the inner edges of the guides. The 55 part t^2 is hinged to the part t at t^6 , and the former has a superposed arm t^8 hinged thereto at t^{10} . The part t^2 is held normally in the same plane with the part t and t^8 in a parallel plane, by a spring t^4 which is secured at one end to the part t , and its other 60 or free end bears upon the arm t^8 . The por-

tion of the transferring device t which engages the perforations or eyes of the successive heddles d , consists of a small collar t^5 adjustably secured in the part t^2 , and which projects from the under side thereof a distance not greater than the thickness of a heddle d , and as a safety catch in addition to the collar t^5 , the end of a screw t^6 which passes through the arm t^8 and the collar t^5 , projects a little beyond the surface of the collar, when the parts t^2 , t^8 are parallel. The 70 movement of the arm t^8 upon its hinge t^{10} , away from the part t^2 , is limited by a stop-screw t^7 , which passes loosely through a hole in that arm and is secured in the part t^2 . The transferring device t is caused to reciprocate in the grooves g^8 , by means of a lever L pivoted at L' to a standard B' , which lever is caused to tilt thereon by a rod L^2 which connects one end of the lever L with a crank-wheel b^5 . This wheel b^5 is supported on a std b^6 secured in a bracket b^7 which projects upward from the carriage A, and it is driven by an attached gear b^8 , which meshes with a gear b^9 on the shaft p^8 . The 75 device t is connected with the opposite end of the lever L by a link L^2 the lower end of which is pivoted to a block L^4 secured to the part t of the transferring device, which will slide up and down in the guide-way when the lever L is tilted. When the device t starts down the guideway, the projecting engaging devices t^5 , t^6 will, by the action of the spring t^4 , be forced successively into the eye or perforation of one of the heddles d . 80 As soon as the engaging device t^5 reaches the eye of the foremost heddle d of the series in the holder R, it will be forced into the eye by the action of the spring t^4 and will start that heddle down the guide-way. During the time that this heddle is being moved a distance about equal to the diameter of the heddle-eye, the safety catch t^6 is held up by means of a ledge g^6 on the inner edge of the guide piece g' , upon which rests a 85 short plate or finger t^8 projecting at one side of the arm t^8 ; then as the transferring devices t , t^2 continue their downward movement, the finger t^8 will pass down through the opening g^5 and the safety catch t^6 will 90 be pressed through the collar t^5 and bear upon the back plate of the guide-way, in position ready to engage the heddle which is being transferred, should the collar t^5 be accidentally disengaged therefrom. Below 95 the opening g^5 a suitable groove g^2 is made for the finger t^8 in the inner edge of the guide piece g' , to hold that finger down until the eye of the heddle which is being transferred is placed accurately in the path 100 of reciprocation of the drawing-in device a' , which is the position shown in Fig. 4. The lower end of the guide piece g' consists of a hinged piece g^8 , in which the groove g^2 is gradually diminished until it ceases near 105 110 115 120 125 130

the point of the piece g^8 , which is held down upon the back plate of the guide-way by a spring g^4 . Consequently, as the transferring device t moves down the guide-way, the finger t^8 will follow the groove g^2 until it reaches the point of the hinged piece g^8 when it will lift the point and pass under it. Immediately the spring g^4 will press the piece g^8 down upon the back plate again, and when the device t starts up the guide-way upon its return movement, the finger t^8 will ride up on to the inclined outer surface of piece g^8 , and thereby successively lift the arm t^3 and part t^2 , and thus withdraw the engaging pieces t^6 , t^5 from the eye of the heddle d . The hinged piece g^8 with its spring g^4 acts like a spring switch, and changes the position of the finger t^8 from the inside of the guide-plate g^7 during its downward course, to the outside of that plate during the upward course. When the device t has completed its upward course and starts down again, the finger t^8 will again pass through the opening g^8 in the plate g^7 , and the part t^2 will again assume the position in a plane parallel with the part t , and as that device continues its movement downward, the engaging collar t^5 will engage the eye of the then foremost heddle d of the series and carry that downward. These operations will be repeated at each reciprocation of the device t .

The operation of the several parts of the machine are timed so that the heddle d which has been deposited at the bottom of the guide-way g , g' will remain there a sufficient length of time for the drawing-in device to pass through the eye and draw a warp-thread back into it, then by means of reciprocating devices h , h' which move across the rear part of the guide-way, the heddle d is ejected from the guide-way and turned to a position at right angles thereto, directed by the curved surfaces h' into the vertically reciprocating supplemental guide h^2 , (see Fig. 9), from which position each heddle d will drop into another reservoir or holder R^2 , where each one is immediately removed from beneath the guide h^2 and the whole are pushed into one or more compact series with their several eyes in linear coincidence, means of a reciprocating block r^3 operated by a link r^4 and swinging lever r^5 on a rock-shaft r^6 , which is operated by the action of a face cam r^7 upon a short arm r^8 secured to the inner end of the shaft r^6 . (See Fig. 2). In a slot upon one side of the holder R^2 near the top, an india-rubber tube or other elastic strip r^{10} is inserted, so as to bear upon the edge of the heddles d and hold them in upright position when dropped into the holder and pushed along therein by the block r^3 . And to insure close contact between the heddles and the strip r^{10} a spring 65 pressed roll r^{11} is attached to a bracket sup-

ported upon the carriage of the drawing-in device in a position to bear upon the strip r^{10} and press it inward, at a point near that at which each heddle first enters the holder R^2 . The supplemental guide h^2 is caused to move downward toward the holder R^2 by interconnecting levers h^3 , h^4 , h^5 , the latter of which is pivoted upon a crank-pin on the disk h^6 Fig. 2.

The ejectors h , h' are supported upon a bar p which is hung by pins p' in slots p^2 of brackets p^1 , secured to the back-plate of the guide-way g , g' . The bar p with the ejectors h , h' is caused to reciprocate, through its connection with a rock-shaft p^4 , by the lever p^5 and link p^6 . The shaft p^4 is caused to rock, by means of a face cam p^7 on the shaft p^8 , which cam acts upon an anti-friction roll p^9 held on a short arm secured to the inner end of the shaft p^4 .

In Fig. 10 is shown an oscillating holder R^{20} with two chambers for the reception of heddles d . This holder R^{20} is caused to oscillate by means of a connecting rod c pivotally attached to a lever c' , which lever is caused to oscillate by the reciprocal action of a cam c^1 on the shaft p^8 , and a spring c^2 . As the movement of the oscillating holder R^{20} is relatively small, it is accommodated by a joint r^9 in the rock-shaft r^6 .

In order to make it certain that each warp-thread has a heddle d strung upon it, stop mechanism is provided, which will be caused to act upon the belt shifter or clutch mechanism and stop the machine, whenever a heddle d is not brought down and deposited in proper position by the transferring device t . This stop mechanism consists of a bell crank latch-lever m pivoted at the lower end of a lever m^2 , which is fulcrumed at m^3 in a part of the machine frame. One arm of the crank-lever m is notched at n upon its under side and extends out over the shifter-bar o ; the other end of the lever m projects upward and is pivoted to a rod m^4 which extends back over the carriage A , and is pivoted to a depending lever m^5 fulcrumed to the machine frame at m^6 . The depending lever m^5 is caused to vibrate by a cam m^7 upon the same shaft with the cams p^7 and r^7 . The vibration of the lever m^5 will, through the rod m^4 , cause the crank-lever m and lever m^2 to vibrate also. A variation of the position of the upper end of the lever M^2 will, as is evident, vary the position of its lower end and of the fulcrum point of the lever n therein.

Referring to Fig. 3, if the upper end of the lever m^2 is moved to the left, its lower end and the pivotal point of the crank-lever m will be moved to the right; this movement, by reason of the rod m^4 holding the upper arm of the lever m stationary, will cause its lower arm to be tilted upward, so that when the whole is swung to the right 130

by the action of the cam m^7 upon the rod m^4 , the notch n of the lower arm of the lever m will pass over the shifter-bar o and permit the machine to continue in operation. If, however, the upper end of the lever m^2 is moved a little to the right, its lower end with the fulcrum of the lever m will be moved to the left, and the notched arm of the lever m will be tilted downward so that the notch n will be below the upper edge of the shifter-bar o ; then when the whole is caused to swing outward by the action of the cam m^7 , the notch n will strike the shifter bar o and push it outward and stop the machine. By means of a spring m^8 attached to the inner end of the rod m^4 , that rod and the lever m are pulled back as soon as the cam m^7 ceases to act. In the upper end of the lever m^2 is an adjustable screw m^9 , the projecting end of which passes through a hole in the back plate of the guideway g, g' , at a point, for instance, a little below the eye of the heddle when it is in position for the warp-thread to be drawn-in, as illustrated in Fig. 4. As soon as the heddle has been brought down to this position by the device t , the cam m^7 acts upon the lever m^5 and rod m^4 and pushes the lever m outward. The screw m^9 having been properly adjusted will bear against the back of the heddle d , and acting through the lever m^2 will move the lever m to the right far enough to cause its notched arm to be raised sufficiently to pass over the shifter-bar o , and produce no action thereon; but if the transferring device t fails to bring down a heddle d to the position mentioned, the end of the screw m^9 will be unobstructed, and the upper end of the lever m^2 will move to the right to its full limit and carry its lower end with the lever m to the left far enough to place the notch n below the upper edge of the bar o , and then when the cam m^7 moves the rod m^4 and lever m to the right, or outward, the notch n will catch upon the bar o , push it outward, and stop the machine, and thus prevent the drawing-in device from drawing a warp-thread without passing through the eye of a heddle d . As soon as the notched lever m releases the shifting-bar o , the latter is returned by the action of a spring, not shown.

The particular form of reservoir or holder for the heddles d is not material, so long as it retains them in a substantially compact mass and in a manner to permit a single heddle at a time to be separated from the mass.

60 We claim:

1. In a machine for drawing warp-threads into detached flat heddles, a drawing-in device; a hopper to support the heddles in a compact mass, each face to face with the adjacent one, mechanism to separate the hed-

dles singly therefrom and successively place them with the eye in the path of reciprocation of the drawing-in device, and means to remove the heddles from such position and place them in symmetrical sequence in one or more series after a warp-thread has been drawn into the eye of each. 70

2. In a machine for drawing warp-threads through the eyes or openings in separate heddles for use in looms, a drawing-in device; a reservoir to hold the heddles in compact series, means to feed them across the reservoir, reciprocating mechanism to engage and successively remove the heddles from the end of the series and transfer each to a position with its eye in the path of reciprocation of the drawing-in device, and means to remove the heddles successively from such position and deposit them in sequence with their respective eyes 80 in linear coincidence. 85

3. In a warp drawing machine provided with a drawing-in device and means to support a cotton harness, a warp and a reed, mechanism to separate the harness eyes, reed dents and warp threads and position them within the path of reciprocation of the drawing-in device, a reservoir to hold detached heddles, such as drop bars, in a compact series and means to separate the heddles singly from the series and to deposit them progressively in position for the successive drawing-in operations corresponding to the positions of the successive harness eyes through which warps are to be 90 drawn. 95

4. In a warp-drawing machine, the combination of a warp-drawing-in device, warp-feeding devices, and mechanism for controlling and manipulating detached drop-heddles, all supported upon a traversing carriage, a loom-reed, loom-harnesses and a warp-holding frame, and mechanism to move one or more of the latter three elements independently of the traversing carriage, and in a direction parallel with the movement thereof. 105 110

5. In a warp-drawing machine, the combination of a warp-drawing-in device, warp-feeding devices and mechanism, for controlling and manipulating detached drop-heddles, all supported upon a traversing carriage, two or more loom-harnesses and a warp-holding frame, and mechanism to move the harnesses and warp-frame, or one 115 or more of them independently of the traversing carriage and in a direction parallel with the movement thereof.

6. In a warp-drawing machine, a reciprocating drawing-in device, warp-feeding 125 devices, mechanism for controlling and manipulating detached heddles, which mechanism consists of a holder for the heddles in mass, means to separate them singly from the mass, a guide to direct the separated 130

5 heddle and means to locate it in position for the drawing-in operation, means to remove the successive heddles from the guide and to deposit them in series, and mechanism to compact the deposited heddles in series, a traversing carriage with which the above-named devices, means and mechanism are adapted to travel, a loom-reed, loom-harnesses, a warp-holding frame, and mechanism to move one or more of the latter three elements independently and differentially in respect to each other and in respect to the traverse of the carriage.

7. In a warp-holding machine, a reciprocating drawing-in device, warp-feeding devices, mechanism for controlling and manipulating detached heddles, which mechanism is adapted to hold the heddles in mass, to separate them singly from the mass, and 15 transfer and locate them successively in position for the drawing-in operation, means to remove the heddles from such position and to deposit them in regular sequence, mechanism to compact the deposited heddles, 20 a traversing carriage with which the above-named devices, means and mechanism are adapted to travel, loom-harnesses, a warp-holding frame and mechanism to move the harnesses and warp-frame, or any number 25 of them, independently and differentially in respect to each other and in respect to the traverse of the carriage.

8. In mechanism for controlling and manipulating detached metallic heddles or similar devices, and placing them in proper 30 position for the drawing-in operation, a holder to support the heddles in compact mass, reciprocating mechanism to separate the heddles singly from the mass and locate them for the drawing-in operations, a 35 spring actuated heddle engaging device carried by the reciprocating mechanism, and means to disengage the said device automatically from the heddle when it has been 40 located for the drawing-in operation.

9. In mechanism for controlling and manipulating detached metallic heddles or similar devices, and placing them in position 45 for the drawing-in operation, a holder to support the heddles in compact mass, heddle separating and transferring mechanism consisting of a reciprocating block which carries a principal heddle engaging device, and an auxiliary engaging device which acts in 50 conjunction with the principal device, and a spring to actuate the two engaging devices.

10. In mechanism for controlling and manipulating separate metallic heddles or similar devices and placing them in position for 55 the drawing-in operation, a holder to support the heddles in compact mass, heddle separating and transferring mechanism consisting of reciprocating mechanism provided with a principal device to first engage

a heddle, and an auxiliary safety device to engage the heddle if released by the principal device after engagement.

11. In mechanism for controlling and manipulating separate metallic heddles or similar devices and placing them in position for the drawing-in operation, a holder to support the heddles in compact mass, heddle separating and transferring mechanism consisting of reciprocating mechanism provided with a principal device to first engage 70 a heddle, an auxiliary safety device, to engage the heddle if released by the principal device after engagement, and means to put the safety device in operative position after the principal device begins to act.

12. In mechanism for controlling and manipulating detached metallic heddles, or similar devices, and placing them in position for the drawing-in operation, a holder 85 to support the heddles in compact mass, reciprocating mechanism provided with a device to engage and separate the heddles singly from the mass, and transfer them successively to position for the drawing-in 90 operation, means to disengage the transferring device automatically from the positioned heddle, and an ejector to remove the heddles successively from such position.

13. In mechanism for controlling and manipulating detached metallic heddles, or similar devices, and placing them in position for the drawing-in operation, a holder to support the heddles in compact mass, reciprocating means to engage and separate 100 the heddles singly from the mass at its forward movement and place them in position for the drawing-in operation, and automatic switching mechanism to disengage the reciprocating means from the heddle, 105 upon the return movement of such means, and to direct it to operative relation with the mass of heddles again, at each forward movement.

14. In mechanism for controlling and manipulating detached metallic heddles, or similar devices, and placing them in position for the drawing-in operation, a holder to support the heddles in compact mass, each face to face with the adjacent one, reciprocating mechanism provided with a device to engage and separate the heddles singly from the mass, and transfer them successively to position for the drawing-in 115 operation, and a spring switch to withdraw the engaging device from the heddle upon the return movement of the transferring mechanism.

15. In mechanism for controlling and manipulating detached flat metallic heddles or similar devices and placing them in position for the drawing-in operation, the combination with a holder to support them in a compact unseparated series each face to 125 face with the adjacent heddle, mechanism 130

to separate the heddles singly from the series and place each in a position for the drawing-in operation, means to remove the heddles from such position after the warp is drawn in and means to deposit such heddles in a plurality of series.

16. In mechanism for controlling and manipulating detached flat metallic heddles or similar devices and placing them in position for the drawing-in operation, a holder to support them in compact unseparated series each face to face with the adjacent heddle, mechanism to separate the heddles singly from the series and place each in position for the drawing-in operation, means to remove the heddles from such position after the warp is drawn in and an oscillating double holder to receive and separate the heddles into two series.

20. 17. In mechanism for controlling and manipulating detached metallic heddles, or similar devices, and placing them in proper position for the drawing-in operation, a holder to support the heddles in compact mass, mechanism to separate the heddles singly from the mass and place each in position for the drawing-in operation, means to remove the heddle from such position after the warp is drawn-in, and a reciprocating device to receive the heddle and guide it to a second holder.

18. In mechanism for controlling and manipulating detached metallic heddles, or similar devices, and placing them in proper position for the drawing-in operation, a holder to support the heddles in compact mass, mechanism to separate the heddles singly from the mass, and to place each in position for the drawing-in operation, means to remove the heddle from such position after the warp is drawn-in, and to deposit it in a second holder and an adjustable friction device to support the heddle therein.

45. 19. In mechanism for controlling and manipulating detached metallic heddles, or similar devices, and placing them in proper position for the drawing-in operation, a holder to support the heddles in compact series, mechanism to separate them singly from the series, to place each in position for the drawing-in operation, to remove the heddle from such position, to receive and guide the removed heddle to a second holder, and means to move each heddle from beneath the guide and compact it with others in the second holder.

20. In a machine for drawing warp-threads into detached metallic heddles, a holder to support a plurality of such heddles, mechanism to separate them singly from the plurality and locate each in a prescribed position, automatic shifting mechanism which is held from action by

the heddle when in the prescribed position, but which acts to stop the machine when no heddle has been there located.

21. In a machine for drawing warp-threads into detached metallic heddles, mechanism to locate the heddles singly and successively in position for the drawing-in operation, and automatic shifting mechanism, which is held from action by the heddle when in said position, but which acts to stop the machine when no heddle has been there located.

22. In a machine for drawing warp-threads into detached metallic heddles, mechanism to place the heddles singly and successively in position for the drawing-in operation, reciprocating means which normally act upon the shifting devices to stop the machine, a lever connected with the reciprocating means, which lever is acted upon by the heddle when in the drawing-in position and holds said means from action upon the shifter.

23. A warp-drawing machine having means for supporting one or more series of interconnected heddles, means for supporting a series of detached members, such as independent heddles, drop bars or the like, and means for positioning said detached members with reference to the eyes of the said interconnected heddles to permit the placing of a thread simultaneously through a selected member of each series.

24. A warp-drawing machine having a thread-placing device, means for supporting a series of interconnected heddles, means for supporting a series of detached members, such as independent heddles, drop bars or the like, and positioning devices for simultaneously positioning a selected member of each series with reference to the line of action of the thread-placing device.

25. A warp-drawing machine having means for supporting one or more series of interconnected heddles, a thread-placing device, means for causing relative traverse between the thread-placing device and the heddles, holding means adapted to hold a series of detached members, such as independent heddles, drop bars or the like, and having a fixed relation to the thread-placing device during the relative traverse between the same and the interconnected heddles, and means for presenting said detached members individually within the line of thread-placing action during the said relative traverse.

26. A machine for handling thin, perforated detached heddles, drop bars or the like, having means for holding a series of such members, means for selecting and positioning the individual members of said series with reference to the line of action of a suitable thread-placing device, and

automatic stop mechanism dependent upon the failure properly to position a member to cause the stoppage of said machine.

27. A warp-drawing machine having a thread-placing device, means for supporting the threads of a warp, means automatically to position the individual members of a series of independent heddles, drop bars or the like with reference to the line of thread-placing action, and automatic stop mechanism controlled by the positioning of said heddles.

28. In a thread placing machine, the combination with a support for detached thread receiving loom elements in which the latter are held in a face to face relation and in a compact unseparated series, of selecting means for selecting the unseparated heddles one by one, thread placing mechanism and means for effecting a symmetrical distribution of the loom elements to a plurality of series in predetermined order.

29. In a drawing-in machine, in combination, means for disconnecting the driving power from the machine; means normally tending to actuate said disconnecting means, and a stop device for said actuating means, said stop device being adapted to be operated upon the absence of a heddle.

30. In a mechanism for acting upon detached metallic heddles, the combination with means for holding the heddles in a series, heddle compacting means, a reciprocatory slide adapted to engage the foremost one of the body of compacted heddles and separate the same from the compacted series, a thread placing device and means to position the separated heddle with its threading-eye in the path of the thread placing device.

31. In a mechanism for acting upon detached metallic heddles, means for holding the heddles of a series, means for compacting the same, a reciprocatory slide having a movement transversely the extent of the series and adapted to engage the foremost one of the body of compacted heddles and separate the same from the series by sliding it across the face of the next adjacent heddle, a thread placing device and means to position the separated heddle with its threading-eye in the path of the thread placing device.

32. A warp drawing-in machine comprising means for supporting a drop wire bar at an inclination to the horizontal, means for retaining and releasing one by one the drop-wires of a compact series supported by said bar, and means for receiving the released drop-wires and presenting them to a drawing-in implement.

33. In a warp-drawing machine, in combination, a hopper for holding detached heddles; a drawing mechanism; and means

automatically actuated for moving a heddle from said hopper to said drawing mechanism.

34. In a warp-drawing machine, in combination, an elevated hopper for holding detached heddles; a drawing mechanism below said hopper; and a chute for guiding heddles from the hopper to the drawing mechanism.

35. In a machine for operating upon detached warp-thread-engaging elements, in combination, a magazine; a chute; an escapement between said magazine and said chute; an operating mechanism; and a positioning means between said chute and said operating mechanism.

36. In a warp-drawing machine, in combination, a drawing mechanism, a stop mechanism for the machine, and a means adapted to engage a certain portion of a heddle for rendering said stop mechanism inoperative.

37. In a machine for operating upon detached warp-thread-engaging elements, in combination, a stop mechanism for the machine; and a member controlling said stop mechanism, adapted to engage said elements and having two operative positions.

38. In a machine for operating upon detached warp-thread-engaging elements, each having an opening therein, in combination, an operating mechanism; means for moving said elements longitudinally to said operating mechanism; and a positioning member adapted to engage in the opening in said element.

39. In a warp-drawing machine, in combination, slotted heddle-guiding means; means for holding a heddle against movement in the slot of said guiding means; means for threading the held heddle; and means for moving the threaded heddle along the slot.

40. A warp-drawing machine comprising means for supporting a warp; means for supporting a harness and a reed; means for supporting a series of detectors, the warp, harness, reed and series of detectors extending in substantial parallelism; means for engaging a thread with a heddle eye, a reed dent and a detector; and mechanisms for aligning said engaging means and successive warp threads, harness eyes, reed dents, and detectors.

41. A warp-drawing machine comprising means for movably supporting a warp; means for supporting a cotton harness and a reed; means for movably supporting a series of detectors, the warp, harness, reed and series of detectors extending in substantial parallelism; a drawing-in needle; and mechanism for aligning successive warp threads, heddle eyes, reed dents and detectors for the action of said needle upon a thread, eye, dent and detector simultaneously.

42. In a machine for threading metallic heddles, the combination with heddle threading means, of means for holding a plurality of flat, metallic heddles in compact series, means to select the heddles one by one from the series and to present the selected heddle in a position certain with its eye portion at right angles to the threading means and its eye in line with the path of movement thereof, and a stop device withheld from action by the heddle when properly presented for the threading action.

43. In a machine for threading metallic heddles, the combination with heddle threading means, of means for holding a plurality of flat, metallic heddles in a compact series, means to select the heddles one by one from said series and to present the selected heddle in a position certain with its eye in line with the path of movement of the threading means, and a stop device controlled by the selected heddle.

44. In a machine for threading metallic heddles, the combination with heddle threading means, of means for holding a plurality of flat, metallic heddles in a compact series, means to select the heddles one by one from said series and to present the selected heddle in a position certain with its eye in line with the path of movement of the threading means, a member adapted to contact with and be displaced by the heddle when the latter is in predetermined position ready for threading, and a stop device controlled by the displacement of said member.

45. In a warp drawing machine, the combination with a thread-placing means, a warp support, means for supporting a plurality of harnesses, means for supporting a series of drop wires, means for selecting the warp threads and placing them successively in the path of the thread placing means, means for positioning a harness eye taken from a selected one of the harnesses in the path of the thread-placing means, means for simultaneously selecting and presenting a drop wire in the path of the thread-placing means, and means for actuating the latter to place a selected thread simultaneously through the selected drop wire and selected harness eye.

46. In a warp drawing machine, the combination with a warp support, of means for supporting a plurality of harnesses, a hopper for holding a series of drop wires, warp-thread selecting means, harness eye positioning means for positioning a harness eye from a selected one of the harnesses to receive a thread, means for withdrawing the drop bars one by one from the hopper and presenting them in position to be threaded, and means for simultaneously placing a selected warp thread through a positioned harness eye and drop bar.

47. In a machine for facing metallic hed-

dles, the combination with a magazine for holding a series of thin, flat metallic heddles, and mechanism for selecting successive heddles from said series, withdrawing each entirely from said magazine, and facing a selected heddle in a certain position.

48. In a machine for threading metallic heddles, the combination with a magazine for holding a series of thin, flat, metallic heddles, means for selecting successive heddles and withdrawing each entirely from said magazine, a reciprocatory drawing-in needle, and means for presenting a selected heddle to face said needle.

49. In a machine for threading metallic heddles adapted to be strung upon a stringer bar, the combination with means structurally independent of a stringer bar for holding a series of flat, metallic heddles, and mechanism to release successive heddles and convey them each to a predetermined position for threading.

50. In a machine for threading metallic heddles adapted to be strung upon a stringer bar, the combination with means structurally independent of a stringer bar for holding a series of flat, metallic heddles, a reciprocatory drawing-in needle, and mechanism to release successive heddles and convey them each to a position facing the said needle.

51. In a machine for threading metallic heddles adapted to be strung upon a stringer bar, the combination with means structurally independent of a stringer bar for holding a series of such heddles, of a thread-placing device, mechanism to release successive heddles and convey them each to a position facing said thread-placing device, mechanism to actuate the thread-placing device, means for holding the threaded heddles in a plurality of series and mechanism for removing the threaded heddles from the threading position and conveying them in predetermined order to said several respective series.

52. In a machine for threading metallic heddles adapted to be strung upon a stringer bar, the combination with heddle threading mechanism, of holding means structurally independent of a stringer bar for holding a series of such heddles, heddle releasing means to release heddles singly and successively and means to distribute the released heddles in predetermined order to a plurality of series.

53. In a machine for threading detached thread-engaging loom elements, the combination with threading mechanism, of a warp support, means to cause relative traversing movement between the warp support and the threading mechanism, means for holding a plurality of said loom elements in a series which extends in a direction transversely the width of the warp, and

means for selecting said elements singly and successively from the series and placing each in a threading position.

54. In a machine for threading detached thread-engaging loom elements, the combination with threading mechanism, of a warp support, means to cause relative traversing movement between the warp support and the threading mechanism, means for holding a plurality of said loom elements in a series which extends in a direction transversely the width of the warp, means for selecting said elements singly and successively from the series and placing each in a threading position and means for placing threaded heddles in a series extending parallel with the extent of the warp.

55. In a machine for threading thin, flat metallic heddles, the combination with a thread-placing device, of means for holding a series of such heddles with their flat faces facing generally the direction of movement of the thread-placing device and mechanism for selecting a heddle from the series and moving it bodily to bring its eye portion within the path of the thread placing device.

56. In a machine for threading thin, flat metallic heddles, the combination with a thread-placing device, of means for holding a series of such heddles with their flat faces facing generally the direction of movement of the thread-placing device and mechanism for selecting a heddle from the series and moving it bodily without turning the same to bring its eye portion within the path of the thread-placing device and means for turning the threaded heddle and conveying it to one or more series.

57. In a machine for threading thin, flat metallic heddles, the combination with a thread-placing device, of means for holding a series of heddles with their flat faces facing generally the direction of movement of the thread-placing device, means to select the heddles singly and successively and convey each to a fixed position without turning the same and with its eye portion within the path of movement of the thread-placing device, means to actuate the thread-placing device to thread the positioned heddle, holding means for holding the threaded heddles in a plurality of series and means to turn each threaded heddle and convey them in predetermined order to said several respective series.

58. In a warp drawing machine, the combination with a hopper for holding detached heddles, thread-placing mechanism, means to release the heddles one by one from the hopper, a chute for guiding a released heddle to a threading position and means for conveying threaded heddles to a compacted series.

59. In a machine for operating upon me-

tallic heddles, the combination with a machine bed, a traveling carriage, mechanism on said carriage for positioning the heddles, heddle holding means also thereon, releasing mechanism for releasing the heddles one by one from the holding means, positioning means and a chute for guiding a released heddle to the position ng means.

60. Mechanism for operating upon metallic heddles comprising a holder for the heddles, releasing mechanism, positioning mechanism and a chute to guide a released heddle to the positioing mechanism.

61. In a machine for acting upon detached metallic heddles, the combination with an elevated hopper for holding such heddles, releasing mechanism for releasing them one by one, positioning mechanism below the level of the hopper for holding a released heddle positioned for subsequent operation and a chute for guiding a heddle from the hopper to the positioring mechanism.

62. In a machine for acting upon metallic heddles, the combination with means for holding a plurality of such heddles, mechanism for releasing them one by one from the holding means and conveying them to a position at a different level and mechanism for positioning them one by one each at its new level for a threading operation.

63. In a machine for acting upon metallic heddles, the combination with means for holding a plurality of such heddles, mechanism for releasing them one by one from the holding means and conveying them to a position at a different level, means for positioning them one by one each at its new level for a threading; operation and means for turning a heddle after the threading operation.

64. In a warp drawing machine for acting upon detached heddles, the combination with means for holding a plurality of such heddles, mechanism for releasing them one by one from the holding means and conveying them to a position at a lower level and for positioning them one by one each at its new level for a thre ding operation.

65. In a machine for acting upon independent heddles, the combination with means for positioning the heddles singly for a threading operation, a device for bunching the threaded heddles and means for reciprocatively actuating it.

66. In a machine for acting upon independent heddles, in combination, a slotted heddle holder for holding a heddle in fixed position to be acted upon and means for moving the heddle along the slot.

67. In a machine for threading flat, metallic detached heddles, the combination with means to hold a series of such heddles in compacted arraement, of mechanism for selecting the heddles one by one from the compacted series by sliding the fore-

- most heddle across the face of the next succeeding one and for positioning the selected heddle for threading and threading mechanism for threading a positioned heddle.
- 5 68. In a machine for threading flat, metallic detached heddles, the combination with means to hold a series of such heddles in compacted arrangement, of mechanism for selecting the heddles one by one from the compacted series by sliding the foremost heddle across the face of the next succeeding one and for positioning the selected heddle for threading, threading mechanism for threading a positioned heddle and means for 70 turning a threaded heddle.
- 10 69. In a machine for threading flat, metallic detached heddles, the combination with a hopper to hold a series of such heddles, mechanism for selecting the heddles one by one from the compacted series by 75 sliding the foremost heddle across the face of the next succeeding one to remove the selected heddle from the hopper and position the same for threading, threading mechanism for threading a positioned heddle and means for placing the threaded heddles in another series outside the hopper.
- 15 70. In a machine for threading flat detached metallic heddles, the combination with means for holding a series of such heddles in compacted arrangement, of mechanism for selecting heddles one by one from the compacted series by sliding the foremost heddle across the face of the next succeeding one in the direction of the length of the heddle and for positioning the heddle for the threading action and threading mechanism for threading a positioned heddle.
- 20 71. In a machine for threading flat metallic detached heddles, the combination with means to hold a series of such heddles in compact arrangement, of mechanism for selecting the heddles one by one from the series by sliding the foremost heddle across the face of the next succeeding one and for positioning the selected heddle for threading, and mechanism for turning a threaded heddle and placing the same in another compact series.
- 25 72. In a machine for threading flat metallic detached heddles, the combination with means to hold a series of such heddles in compact arrangement, of means comprising a reciprocating slide for selecting the heddles one by one from the series by sliding the foremost heddle across the face of the next succeeding one and for positioning the selected heddle for threading and mechanism for threading a positioned heddle.
- 30 73. In a machine for handling flat metallic detached heddles, the combination with a magazine to hold a series of such heddles in compact arrangement, of mechanism for separating the heddles one by one by causing the foremost heddle to slide across and in contact with the face of the next adjacent one and thereby away from the compact series and out of the magazine, guiding means to guide the heddle to a fixed position for a subsequent operation and means to place heddles when operated upon in another series.
- 35 74. In a machine for threading flat metallic detached heddles, the combination with means to hold a series of such heddles in compact arrangement, mechanism for selecting them one by one by sliding the foremost heddle across the face of the next succeeding one and for positioning the selected heddle 80 without turning the same for the threading operation.
- 40 75. In a machine for acting upon detached metallic heddles, the combination with a thread-placing device, a hopper, of means for releasing the heddles singly from said hopper and placing each in a position to be threaded and means to distribute the threaded heddles to a plurality of series.
- 45 76. In a machine for acting upon flat metallic detached heddles, the combination with a hopper for holding a plurality of such heddles in a compact unseparated series, a threading device, mechanism for separating the heddles one by one from the hopper to pass each one to a threading position and thence on out of the threading position and mechanism acting upon the heddles in the course of their passage for distributing them in a plurality of series.
- 50 77. In a warp drawing machine, in combination, a heddle hopper, releasing means, means to guide a released heddle in its movement toward a threading position, a plurality of heddle holders and movable means for directing heddles from said guiding means to said holders, the latter taken in predetermined order.
- 55 78. In a machine for acting upon flat metallic detached heddles, the combination with means for holding a plurality of such heddles in compacted series, means to select the heddles singly from said series and place them each in a position to be threaded and means to turn the heddles each when threaded and distribute them to a plurality of series.
- 60 79. In a machine for threading metallic heddles, the combination with means for holding a series of such heddles, of a thread placing device and means for selecting the heddles one by one from the series and conveying them away from and out of line with said series to a threading position.
- 65 80. In a machine for threading metallic heddles, the combination with means for holding a series of such heddles, of a thread-placing device, means for selecting the heddles one by one from the series and conveying them bodily away from and at one side

of the line of the series to a threading position.

81. In a machine for threading metallic heddles, the combination with means for holding a series of such heddles, of means for selecting the heddles one by one from the series and conveying them away from and out of line with said series to a threading position, means for threading a positioned heddle and means for placing a threaded heddle in another series. 45

82. In a machine for acting upon metallic heddles, the combination with a hopper, a guide, means to select the heddles one by one and slide them each out of the hopper and through the guide to a threading position, a turning device and means to distribute the threaded and turned heddles to a plurality of series. 50

83. In a machine for acting upon metallic heddles, the combination with a hopper to hold a series of heddles, means to slide the heddles one by one out of the hopper to a fixed position for a subsequent operation and means to turn a heddle after being operated upon and pass the same to another series. 55

84. In a machine for threading metallic heddles, the combination with means for holding the same in compact series, a warp support, thread selecting means, a reed support, reed opening means, means to select the heddles one by one from the series and position the same for threading, threading mechanism to place a selected thread through a positioned heddle and opened reed dent and means to distribute threaded heddles into a plurality of series. 60

85. In a machine for acting upon metallic heddles, the combination with means for

holding a plurality of such heddles, a thread placing device, and means to release the heddles singly and successively by moving the foremost heddle in a direction lengthwise the heddle and conveying it to a threading position. 45

86. In a machine for handling metallic heddles, the combination of the heddle holder R, the selecting device t for selecting heddles from the holder, the positioning device g, g' for positioning a selected heddle, and the thread-placing device a' for threading a positioning heddle. 50

87. In a machine for handling metallic heddles, the combination of the heddle holder R', the selecting device t for selecting heddles from the holder, the positioning device g, g' for positioning a selected heddle, the thread-placing device a' for threading a positioning heddle, the coöperating, ejecting and turning devices h, h and h', h', and the heddle holder R'. 55

88. In a machine for handling drop bars, the combination of the drop bar holder R', the selector t' for selecting drop bars from the holder, coöperatively arranged supports for the harnesses H, H, harness eye selecting devices i, the warp support W, the warp thread selector s², the drop bar positioning device g, g', the thread-placing device a' for 60 threading harness eyes and drop bars with warp threads, and the holder R² for the threaded drop bars. 70
